US00D763947S

(12) **United States Design Patent**
Shin

(10) **Patent No.:** **US D763,947 S**
(45) **Date of Patent:** **** Aug. 16, 2016**

(54) **EYEGLASSES**

(71) Applicant: **Oakley, Inc.**, Foothill Ranch, CA (US)

(72) Inventor: **Jae Shin**, Irvine, CA (US)

(73) Assignee: **Oakley, Inc.**, Foothill Ranch, CA (US)

(**) Term: **15 Years**

(21) Appl. No.: **29/540,370**

(22) Filed: **Sep. 23, 2015**

FIG. 1 is a front perspective view of eyeglasses showing an embodiment of the new design;
FIG. 2 is a front elevational view thereof;
FIG. 3 is a rear elevational view thereof;
FIG. 4 is a left side elevational view thereof, the right side elevational view being a mirror image thereof;
FIG. 5 is a top plan view thereof; and,
FIG. 6 is a bottom plan view thereof.
Broken lines and unshaded portions contained within broken lines depict portions of the eyeglasses that form no part of the claimed design.

1 Claim, 5 Drawing Sheets
